UNITED STATES PATENT OFFICE.

JOHN W. THOMASON, OF SALADO; TEXAS.

CAR-COUPING.

SPECIFICATION forming part of Letters Patent No. 249,695, dated November 15, 1881.

Application filed March 28, 1881. (No model.)

To all whom it may concern:

Be it known that I, JOHN W. THOMASON, of Salado, Bell county, Texas, have invented a new and useful Improvement in Car-Couplings; and I do hereby declare that the following is a full, clear, and exact description of the same, reference being had to the accompanying drawings, forming part of this specification, in which—

10 Figure 1 is a side elevation of my invention. Fig. 2 is a vertical longitudinal section. Fig. 3 is a bottom plan view. Fig. 4 is a section on the line A A of Fig. 2. Fig. 5 is a perspective view, showing the means of attaching my coupling to a locomotive.

15 My invention relates to improvements in car-couplings; and it consists, first, of certain devices whereby the coupling-pin raised in the draw-head is supported until the draw-heads 20 strike each other in coupling, when the coupling-pin falls by gravity.

25 My invention further consists of devices whereby a link or pin may be raised separately or both raised simultaneously, as the case may require, in coupling cars.

30 My invention also consists in certain details of construction hereinafter more fully described.

35 My invention further consists in the peculiar 30 construction of a link attached to the cow-catcher of a locomotive, as hereinafter more fully set forth.

In the accompanying drawings, *a* is the platform form of a car, to the under side of which the 35 draw-head *b* is attached in the usual manner. The draw-head *b* is provided with recesses *c* on each side, each having holes in its end bars, *d*, for the passage of rods *e*, secured to the face-plate *f*, provided with a central opening fitting 40 over the mouth of the draw-head.

To the inner ends of the rods *e* is secured a connecting-rod, *g*, one end of which engages with a hook on a lever, *h*, pivoted on the under face of the platform, whereby the face-plate can be moved inwardly against the tension of the spiral springs *i*, arranged in the recesses *c* and surrounding the rods *e*. A lever, *h*, is employed on each side of the draw-head to draw back the face-plate *f*, held out by the 45 tension of the spiral springs *i*. The face-plate *f* is provided with an inwardly-projecting plate, *k*, fitting in a recess in the upper part

of the mouth of the draw-head, said plate *k* being adapted to slide in said recess as the face-plate *f* is moved back and forth. A hole 55 is formed in the upper end of the draw-head for the passage of the coupling-pin, and through the plate *k*. These holes register with each other when the face-plate *f* is drawn back by the levers *h*, allowing the pin to fall down 60 through the link; but when the levers *h* are not operated and the face-plate is held out by the tension of the springs *i* these holes do not register with each other, and the coupling-pin is supported in an upright position by the 65 plate *k*. By drawing back the levers *h* the holes are made to register and the coupling-pin falls into position in the link by gravity.

70 *l* is a rack-bar adapted to slide vertically in an opening in the platform and draw-head.

75 *m* is a horizontal shaft journaled in the draw-head, and carrying a pinion, *n*, gearing into the rack-bar and operated by a crank on the end of the shaft *m* for freight-cars to raise and lower the rack-bar. For passenger-cars a vertical shaft projecting upward through the platform, connected by suitable gearing with the shaft *m*, is employed to operate said shaft and raise or lower the rack-bar. The rack-bar is 80 held in any desired position by means of a pawl, *o*, on a rock-shaft, *p*, journaled in the back part of the draw-head, said pawl engaging with the pinion *n* when the rock-shaft *p* is turned in one direction and disengaged therefrom when the rock-shaft is turned in the opposite direction. 85

The upper end of the rack-bar *l* is cut away and provided with a recess, *q*, for the reception of the projection *r* of the sliding plate *s*. The recess *q* is made longer than the projection *r*, so that the latter may be moved vertically therein, and the projection *r* is provided with a screw-threaded hole, *t*, for the reception of the screw *u*, passing also through a screw-threaded hole in the top of the rack-bar, whereby the sliding plate *s* can be adjusted vertically on the link 90 held between the lower edge of the sliding plate, and in a recess, *v*, for the link made in the rack-bar. By this construction links of varying thickness may be employed in coupling cars and held horizontally in the rack-bar, 100 which latter, by means of the pinion, may be adjusted for cars of different heights.

The upper horizontal face of the rack-bar *l* is recessed for the reception of a sliding plate,

w, provided with a slot, x, for the passage of the screw u, that adjusts the sliding plate s vertically; and the plate w is provided at its front end with a recess and projecting arms y for engaging under the head of the coupling-pin z. The upper face of the sliding plate w is also provided with an upwardly-projecting cam, a', which is made to engage with a cam-plate, b', journaled on the screw u. The outer end of the cam-plate b' is provided with a handle, by which it may be rocked, thus moving out or in the sliding plate w. A spring may be employed, if desired, to throw the sliding plate w forward after it has been retracted, to release the head of the coupling-pin. The head of the coupling-pin is preferably cone-shaped. Each of the cars is provided at each end with coupling devices, as above described.

In practice, to couple two cars the link is held in one of the cars horizontally in the recess in the rack-bar, and the latter, with the link, can be raised or lowered to suit the height of the car to be coupled and held in position by the pawl. In the opposite car to be coupled the coupling-pin is raised and supported in its raised position by the flange of the face-plate, and the link enters the draw-head of the car to be coupled, and the face-plates coming in contact with each other, the holes in the flange and draw-head register and the coupling-pin falls by gravity through the link. By operating the draw-head levers, in case the face-plates should fail to strike, the coupling-pin would fall by gravity through the link.

To uncouple two cars, the sliding plate is made to engage with the head of the coupling-pin and the rack-bar is operated, raising the coupling-pin, which is held raised by the pawl. In coupling, the end of the link in the recess in the rack remains therein until pulled out by the forward movement of the cars, when it is caught by the coupling-pin.

It will be seen that in my invention the cars are coupled and uncoupled from the sides of the cars or platforms, and there is no liability of the operator being caught between the cars in coupling or uncoupling them.

In Fig. 5 is shown a link pivoted to the cow-catcher of an engine and operating upon the same principle as the coupling hereinbefore described. This link, hinged to the front of the cow-catcher, consists of a bar, c', provided at its forward end with a cross-bar, d', and a link, e', secured to the front thereof.

In coupling the engine to a car provided with a draw-head constructed as in my invention, the bar c' is raised or lowered by means

of the rock-shaft h', carrying the crank k', pivoted to the bar c' by the link l', until the link e enters the draw-head of the car to be coupled, 60 the coupling-pin being raised, and when the cross-bar d' strikes the face-plate f the coupling-pin falls by gravity and the car is coupled to the engine.

What I claim as my invention is— 65

1. The combination, with the draw-head b, provided with a recess and hole for the coupling-pin in its upper end, of the face-plate f, provided with an inwardly-projecting plate, k, having a hole for the passage of the coupling- 70 pin, springs i, levers h, and coupling-pin z, substantially as described, and for the purpose set forth.

2. The combination, with the draw-head b, of the rack-bar l, shaft m, carrying the pinion 75 n, and rock-shaft p, carrying the pawl o, substantially as described.

3. The combination, with the rack-bar l, having a recess, q, of the sliding plate s, provided with the projection r, having a screw-hole and screw, u, whereby the link may be held horizontally and raised or lowered, as desired, substantially as described. 80

4. The combination, with the rack-bar l, of the sliding plate w, having slot x, arms y, and 85 cam a', and the cam-plate b', substantially as described, and for the purpose set forth.

5. The combination, with the rack-bar l, of the sliding plate s, having projection r, screw u, sliding plate w, having slot x, arms y, and 90 cam a', and cam-plate b', substantially as described, and for the purpose set forth.

6. The combination, with the draw-head b and coupling-pin z, of the sliding plate w, having slot x, arms y, and cam a', of the cam-plate 95 b', provided with a handle, and screw u, substantially as described.

7. The combination, with the link composed of the bar c', cross-bar d', and link e', hinged to the cow-catcher, of the draw-head b, having face-plate f, and coupling-pin z, substantially as described. 100

8. The bar c', hinged to the cow-catcher and provided with the cross-bar d' and link e', substantially as described. 105

9. The combination, with the hinged bar c', having the cross-bar d', and link e', of the rock-shaft h', having the crank k', and pivoted link l', substantially as described.

JOHN W. THOMASON.
